ABSTRACT OF THE DISCLOSURE

A mobile marine drilling apparatus including an independent mobile derrick support which carries a drilling derrick including the supplementary equipment therefor and an independent mobile marine auxiliary platform adapted to be brought around the derrick support, attached thereto and raised by the supplementary derrick equipment including the traveling block. The auxiliary platform can be used to stabilize the derrick support and to raise and lower the derrick support.

Marine platforms which are mobile and carry the means necessary to anchor at desired offshore locations for drilling of oil wells therefrom are well-known at the present time. While of many and varied constructions, marine platforms generally are supported in operative position by means of a plurality of cylindrical members or columnar structures which are anchored on the sea bottom and rise vertically therefrom to the platform. For example, U.S. Patent 3,093,972 discloses a mobile marine platform and a frame adapted to be submerged with the platform subsequently being raised by the use of the frame to a desired elevation above the water surface. However, this type of portable platform lacks stability, especially while being transferred, i.e., floated from one location to another, since vertical positioning of the frame tends to substantially raise the center of gravity of the platform thereby making it unseaworthy.

The present invention overcomes the disadvantages of the prior construction by providing an offshore exploration and production assembly including an independent mobile marine auxiliary floating platform and a derrick platform which has its own independent mobile marine support and which carries a drilling derrick including the supplementary equipment therefor such as the traveling block. The derrick support is stabilized by legs appended thereto and spread out beneath the waves, thus presenting a stable structure which can operate in and above several hundred feet of water. When desired, the floating auxiliary platform is brought around the support for the derrick platform and attached thereto and the traveling block on the drilling derrick is used to raise and lower the auxiliary platform with respect to the derrick support. Using the traveling block to raise or lower the auxiliary platform eliminates the usual additional mechanisms associated with raising or lowering working platforms above water and renders it possible to use the auxiliary platform as a floating dock alongside which boats may be tied to load or unload cargo or crews in high seas in a much safer and more convenient manner than has heretofore been possible under such circumstances. This is possible because there is only one support for the auxiliary platform around which it may rock in the waves. This would not be possible if there were the usual multiple supports. By counterlevering the auxiliary platform on the derrick support, a minimum amount of support area is exposed to the wave forces. In further usage, the auxiliary platform provides a means for easily removing the exploration appurtenances, and the derrick platform and support may be

2

left, if desired, to serve as a production station for the well, or wells, after they have been developed.

The offshore exploration and production apparatus of the present invention is further described with reference to attached drawings in which:

FIGURE 1 is a side elevational view of the assembly of the present invention in which the auxiliary platform is mounted in an elevated position above the water surface;

FIGURE 2 is a plan view of the assembly;

FIGURE 3 is a partial side view of FIGURE 2 showing in more detail the relationship between the auxiliary platform and the derrick support which is in a raised position;

FIGURE 4 illustrates in detail a portion of the attachment of the auxiliary platform to the derrick support; and

FIGURES 5A-C illustrate in combination with FIGURE 1 the operation of the auxiliary platform and derrick support.

Referring now to FIGURES 1 and 2, the assembly of the present invention comprises a derrick 14, derrick support 16 and auxiliary platform 12. Derrick support 16 includes a vertical section 16' which in use extends below the water surface 24 and has legs 18 spreading therefrom to feet 20 to support the assembly on the ocean bottom 22. Derrick 14 is supported on a derrick platform 10 which is movably supported on derrick support 16, particularly section 16'. The auxiliary platform 12 is of general U-shape including a slot 12' which fits around the derrick support section 16' and is attachable thereto in raised position by pins (not shown) such as pins 15, see FIGURE 3. The auxiliary platform 12 is also engagable with elements of the drilling rig associated with the derrick 14, including traveling block 26, by cables 28' and is adapted to be raised and lowered with respect to derrick support 16 by traveling block 26 and cables 28'. Cables 28, also shown, are attached to the auxiliary platform 12 and the derrick support 16 for raising and lowering the support 16 with respect to the auxiliary platform 12 by means of the traveling block 26. Traveling blocks and the required motive means therefor are well known to one skilled in the art and, in general, are used to raise and lower equipment, e.g., drill pipe sections, with respect to the derrick 14. Rubber tired rollers 30 as shown in FIGURE 4 are preferably attached to auxiliary platform 12 so that during raising and lowering, or floating of platform 12 it can roll, e.g. with the waves at the ocean surface 24 without damage to derrick support 16. Rollers 30 are preferably spring-mounted to take up any slack between platform 12 and support 16. When platform 12 is at the desired level, pins 15 are inserted in derrick support 16 to support platform 12 and release the traveling block 26 for drilling operations. Derrick platform 10 is moveable with respect to derrick support 16 by, e.g., screws 32 which are operated by motor 34 to keep the drilling platform level and in its original position during drilling operations.

Feet 20 which are used to support the assembly on bottom 22 are hollow bodies sufficiently heavy in construction to withstand the high pressures to which they are subject when exposed several hundred feet beneath the water. Each of the feet is a pontoon and is preferably provided with a relief valve to prevent the possibility of dangerously high pressure building up within the confines thereof. The pontoon feet 20 are used to float the derrick support 16 for relocation. When it is desired to move the drilling rig, auxiliary platform 12 is lowered to the water surface and water jets 21 in the bottom of the pontoons, operable from the platform, e.g., auxiliary platform 12, are actuated to break the suction grip which develops if the pontoons sink in the bottom. Pumps on the platforms 10 or 12 then restore partial buoyancy to pontoons 20 so that

they may be raised off the bottom by cables 28' and traveling block 26, as shown in FIG. 5C, to facilitate relocation of the drilling rig.

In positioning the drilling rig for drilling operations, the derrick platform 10 and derrick support 16 together with auxiliary platform 12, are towed, e.g., by tugs, from the construction site or former drilling location to the new drilling location in the positions shown in either FIGURE 5A or 5C, for example. When in the position of FIGURE 5A, auxiliary platform 12 and the towing tugs are then attached one to each of the pontoon feet 20 of the derrick platform support 16 at the drilling location by means of hoist cables, not shown, to act as stabilizers, as the whole framework is sunk to the bottom in the design area. The slot 12' in the auxiliary platform is then brought around the derrick support 16 as shown in FIGURE 5B. Cables 28' are then attached to the auxiliary platform, and to traveling block 26 while it is in a lowered position. The auxiliary platform 12 is then raised by cables 28' and traveling block 26. Since derrick support 16 rests on the ocean bottom 22, raising of the traveling block raises platform 12 with respect thereto. Auxiliary platform 12 is secured as shown in FIGURE 1, e.g., by pins, to derrick support 16 at the desired level, to provide additional working area. Auxiliary platform 12 can be easily raised and lowered by cables 28', when desired, to surface 24 to provide a floating dock for loading or unloading of cargo or crews. After the well is drilled, to float the rig to a new location, the auxiliary platform is lowered to the water by cables 28' and traveling block 26, and cables 28 are attached to the traveling block in its lowered position. Raising of the traveling block now raises derrick support 16 and derrick 14 from the bottom, using auxiliary platform 12 as a stabilizer, see FIGURE 5C. In this position, since the auxiliary platform 12 is floating, it provides a support base and the derrick support 16 can be raised and lowered with respect thereto. After the rig has been thus floated, it is transported to the new location, the derrick support is lowered to the bottom by cables 28 using auxiliary platform 12 as a stabilizer and the auxiliary platform 12 is again raised by cables 28' and attached to derrick support 16 in the drilling position, as described above.

It is claimed:

1. An assembly for arranging and supporting a working area over a body of water which consists essentially of derrick support means including a vertical portion extending both above and below the surface of the water and leg means for supporting the assembly on the bottom of said body of water, a derrick platform supported by and movable vertically with respect to said derrick support means, means for moving said derrick platform with respect to said derrick support means, means for securing said derrick platform to said vertical portion at selected positions thereon, derrick means on said derrick support means including traveling block means for raising and lowering equipment with respect to said derrick means, a floatable auxiliary working platform having a recessed portion on one side separably attachable to said derrick support means at said recess and movable vertically with respect to said vertical portion, means for securing said auxiliary platform to said vertical portion at selected positions thereon, and means including said traveling block means for raising and lowering said auxiliary working platform with respect to said derrick support means whereby said auxiliary working platform and said derrick platform are separably movable with respect to each other and to the surface of said body of water.

2. The structure of claim 1 wherein said means for

raising and lowering the auxiliary platform are cables attached to said traveling block means.

3. The structure of claim 2 wherein said means for securing said auxiliary platform to the vertical portion are pins.

4. The structure of claim 2 wherein the means for raising and lowering the derrick platform is a motor and screw means.

10 5. The structure of claim 2 wherein roller means are attached to said auxiliary platform to cushion its movement against said vertical section.

15 6. A method for providing a work area over a body of water utilizing a structure as defined in claim 2 comprising submerging said derrick support means until said legs rest on the bottom of said body of water, lowering the traveling block means to said derrick platform, attaching the traveling block means to the cable for raising and lowering the auxiliary platform, raising the traveling block means until said auxiliary platform is at one of said selected positions therefor, and securing said auxiliary platform to said vertical portion.

20 7. A system for establishing a drilling rig for operation in a body of water to explore the ground submerged by the water, comprising: a derrick support, a drilling derrick and an adjustable derrick platform supported by the derrick support, said derrick support having at least three spread legs with pontoon feet constructed for surface travel on a body of water and adapted to be flooded and submerged to the bottom and including means for restoring buoyancy to the same, a buoyant auxiliary platform constructed to fit around the derrick support on three sides and adapted to float apart from the derrick support while the latter is bottomed and to be brought around the derrick support, means for raising the auxiliary platform above the surface of the water including means operable from the derrick platform on the support so that the two platforms may be used together to carry out the exploration, and means for lowering the auxiliary platform to float on the water around the body framework to act as a floating dock to load or unload crews or cargo, and means for raising the derrick support operable from the derrick platform so that the derrick support and auxiliary platform can be floated to a new location in the same area, and means for lowering the derrick support to the bottom whereby the auxiliary platform can again be raised; and means for keeping the derrick platform level as drilling progresses including means for raising and lowering the derrick platform with respect to the derrick support.

25 8. A system as defined in claim 7 further including water jet means in the bottom of the pontoon feet operable from the derrick platform to break the suction grip which develops if the pontoon feet sink in the bottom.

30 9. A system as defined in claim 7 including means for securing the auxiliary platform at the level of said derrick platform.

35 10. A system as defined in claim 7 wherein the drilling derrick includes traveling block means and said means for raising and lowering the auxiliary platform comprises cables attached to the auxiliary platform and the traveling block means.
